UNITED STATES PATENT OFFICE.

MORRIS P. BRAY, OF BIRMINGHAM, CONNECTICUT.

DESIGN FOR A CORSET.

Specification forming part of Design No. **11,127**, dated April 1, 1879; application filed February 17, 1879.
[Term of patent 14 years.]

To all whom it may concern:

Be it known that I, MORRIS P. BRAY, of Birmingham, in the county of New Haven and State of Connecticut, have invented a new Design for Corsets; and I do hereby declare the following, when taken in connection with the accompanying drawings and the letters of reference marked thereon, to be a full, clear, and exact description of the same, and which said drawings constitute part of this specification, and represent, in—

Figure 1, view of one-half of a corset.

This invention relates to a design for a corset; and consists in plain vertical sections, varying in width according to the different parts of the corset, and alternating with ornamented vertical sections of equal width, as shown in the accompanying illustration.

The form or cut of the corset is immaterial

to this design. Onto the outer surface of the corset I place strips A of a figured fabric, and of equal width from top to bottom, leaving spaces or sections B of the body exposed between the strips A, and varying in width according to the form of the corset. This gives to the corset a finished appearance, and as of more complicated workmanship than it in reality is.

I claim—

The herein-described design for a corset, consisting of the plain vertical strips B, varying in width and alternating with the ornamented vertical strips A, of equal width, as shown in the accompanying illustration.

MORRIS P. BRAY.
